United States Patent Office

Des. 204,856
Patented May 17, 1966

204,856

PIPE HOLDER OR SIMILAR ARTICLE

Domenick F. Loscalzo and Anthony J. Barsanti, both of
New York, N.Y., assignors to Visionade Manufacturing
Co., Inc., Brooklyn, N.Y., a corporation of New York

Filed Sept. 10, 1965, Ser. No. 86,983

Term of patent 14 years

(Cl. D85—8)

FIG. 2

FIG. 1

FIG. 3

FIG. 4

FIG. 6

FIG. 5

FIG. 1 is a top plan view of a pipe holder embodying the invention;

FIG. 2 is an end view thereof, looking from the right side of FIG. 1;

FIG. 3 is a side elevational view thereof;

FIG. 4 is an end view thereof looking from the left side of FIG. 1;

FIG. 5 is a bottom plan view thereof; and

FIG. 6 is a longitudinal cross-sectional view taken on line 6—6 of FIG. 1.

We claim:

The ornamental design for a pipe holder or similar article, substantially as shown.
